(57) **CLAIM**

The ornamental design for a rotatable cupholder, as shown and described.

DESCRIPTION

FIG. 1 is a top, back, left perspective view of a rotatable cupholder design in a first configuration of use;

FIG. 2 is a bottom, back, right perspective view thereof;

FIG. 3 is a top plan view thereof;

FIG. 4 is a bottom plan view thereof;

FIG. 5 is a front elevation view thereof;

FIG. 6 is a back elevation view thereof;

FIG. 7 is a left side elevation view thereof;

FIG. 8 is a right side elevation view thereof;

FIG. 9 is a back, right elevation view of the rotatable cupholder, shown in a second configuration of use;

FIG. 10 is a left side elevation view of the rotatable cupholder shown in the first configuration of use attached to an armrest of a combined bench and table;

FIG. 11 is a left side elevation view of the rotatable cupholder shown in the second configuration of use attached to the armrest of the combined bench and table;

FIG. 12 is a front elevation view of the rotatable cupholder shown in the first configuration of use attached to a right armrest of the combined bench and table;

FIG. 13 is a front elevation view of the rotatable cupholder shown in the second configuration of use attached to the right armrest of the combined bench and table; and,

FIG. 14 is a left side perspective view of the rotatable cupholder shown in the second configuration of use attached to the right armrest of the combined bench and table.

The broken lines immediately adjacent to the shaded areas represent the bounds of the claimed design while all other broken lines represent portions of the article and form no part of the claimed design. In FIGS. 10-14, the bench and secondary cupholder shown in broken lines represent environmental components and form no part of the claimed design.

1 Claim, 10 Drawing Sheets
